UNITED STATES PATENT OFFICE.

WILLIAM C. FERGUSON, OF ST. LOUIS, MISSOURI.

SERIES OF SEWERS OR CONDUITS.

Application filed April 14, 1922. Serial No. 552,579.

To all whom it may concern:

Be it known that I, WILLIAM C. FERGUSON, a citizen of the United States, residing at St. Louis, Missouri, have invented a certain new and useful Improvement in Series of Sewers or Conduits, of which the following is a full, clear, and exact description, such as will enable others skilled in the art to which it appertains to make and use the same.

This invention relates to sewers, conduits and other tubular structures of the kind that comprise a double circular wall whose inner portion is composed of segmental blocks or tile. In building double wall structures of the general type referred to in which the outer and inner portions of the wall are composed of outer and inner segmental blocks or tile arranged in interlocking relation it is now the universal custom to vary the dimensions of both the inner and outer blocks when the diameter of the structure is to be varied. For example, if the conduit to be constructed is to have a diameter of 72 inches, it is the practice to use inner blocks having an inside width of 11.01 inches and outer blocks having an inside width of 11.40 inches, and if the conduit to be constructed is to have a diameter of 54 inches, it is the practice to use inner blocks having an inside width of 10.28 inches and outer blocks having an inside width of 10.72 inches. Also in structures where the inner portion of the circular wall is composed of segmental tile and the outer portion of the wall is constructed of different material it is the custom to use different sized blocks or liners for different sized sewers. Accordingly, the cost of building sewers and conduits of the general type above referred to is increased considerably by reason of the large number of dies that are required to form the different sized blocks or tile and by reason of the large stock of blocks or tile it is necessary to keep on hand to supply orders for sewers of conventional sizes ranging from 30 inches to 72 inches in diameter, with a variation of 3 inches between the different sizes. Moreover, the above method of constructing sewers and conduits gives very little latitude in changing a particular structure to meet or overcome special conditions, due, of course, to the fact that blocks or tile designed for a sewer of a particular diameter

can be used only in the construction of a sewer of that diameter, or approximately that diameter.

The present almost universal practice in sewer construction is for the use of sizes varying from each next size larger or smaller by 3 inches, and one object of this invention is to provide a method of constructing a double wall sewer or conduit, by which the addition of one unit to a standard size sewer will give the next standard size sewer without the necessity of providing specially designed blocks for the different sizes.

Another object is to provide a method of constructing double wall sewers, conduits and the like which reduces the number of variable elements on such structures, or, in other words, reduces the number of different sized blocks that are required in the construction of a series of sewers of conventional diameters, say, for example, fifteen sewers ranging from 30 inches to 72 inches in diameter.

Another object is to provide a method of constructing double wall sewers or conduits that permits great flexibility in construction, so that when greater loads are encountered, the required strength may be obtained simply by a different arrangement of the various units, thus overcoming the necessity of re-designing the individual units to meet each different condition.

And still another object is to provide an inner block or tile for sewers or conduits which is so proportioned and designed that it is capable of being used with all of the various sizes of sewers which are now standard, namely, sewers in which the variation in diameter between the different sizes is 3 inches.

To this end I have devised a method of constructing a series of double wall sewers or conduits of different diameters, that is characterized by using a universal inner block or tile of standard shape and dimensions for all sewers of the series.

Figure 1 of the drawings is a diagrammatic view, illustrating my invention applied to a double wall sewer or conduit whose inner and outer portions are composed of segmental tile; and

Figures 2, 3, 4 and 5 are sectional views, illustrating the construction of the universal inner blocks and the different sized outer blocks used in the construction of the dif-

ferent sized sewers that make up the complete series.

- The complete series preferably comprises fifteen sewers or conduits ranging in diameter from 30 inches to 72 inches, and varying from each other in size by a difference of 3 inches in diameter, it being the almost universal practice at the present time in sewer construction to use sizes that vary from each next size larger or smaller by 3 inches. Each conduit of the series is provided with a double circular wall composed of an inner portion formed of inner segmental blocks and an outer portion that surrounds said inner tile. In the form of my invention herein illustrated the outer portion of the wall is composed of outer segmental blocks arranged in interlocking relation with the inner blocks with the joints and spaces between said blocks filled with mortar, cement or the like. I wish it to be understood, however, that it is immaterial, so far as my broad idea is concerned, how the outer portion of the wall of the sewer is constructed, so long as the inner portion of the wall is constructed of universal segmental blocks of standard dimensions that are capable of use with any of the various sized sewers of the entire series. The inner blocks A used in all of the fifteen different sized conduits of the series are of the same shape and dimensions, and therefore, will be referred to as universal inner blocks. In a structure of the particular type herein shown the outer blocks used in the different sized conduits are of different dimensions, however, and constitute a set or group of different sized blocks. For example, one outer block B₁ of the set or group, having certain dimensions, can be used to construct conduits ranging in diameter from 30 inches as a minimum to 42 inches as an ordinary maximum, another outer block B₂ of the set, having different dimensions, can be used to construct conduits having diameters ranging and varying every 3 inches from 42 inches as an ordinary minimum to as high as 51 inches as an ordinary maximum, another outer block B₃ having different dimensions, can be used to form conduits ranging and varying in diameter by 3 inches from an ordinary minimum diameter of 51 inches to an ordinary maximum diameter of 60 inches, and another outer block B₄ of the set having different dimensions, can be used to construct conduits having an ordinary minimum diameter of 60 inches and varying by 3 inches up to an ordinary maximum diameter of 72 inches. While the outer blocks constituting the set differ in dimensions, they are of the same general design, in that each is provided on its inner side with a longitudinally-disposed center groove 1 that is adapted to receive longitudinally-extending side ribs 2

on two adjacent inner blocks A, the spaces and joints between the co-operating surfaces of the inner and outer blocks of the structure being filled with cement, mortar or other suitable material. Whatever type of structure the universal inner blocks A are used with, each of said blocks A must be of a certain width, it must be provided with a concaved inner surface 3 of a certain curvature and it must be provided with longitudinal side edges 4 that are disposed in a certain relation to the inner surface 3 of the block. In order that the blocks A will be universal for all sizes of sewers used in common practice, the three elements above mentioned must be governed by certain principles. Thus, the width of the face 3 of each of the inner blocks A must be such that when twenty-four of such blocks are assembled around a circular form, they will form a cylindrical shell having a diameter of 72 inches; when twenty-three of said inner blocks are assembled around a circular form, they will form a cylindrical shell having a diameter of 69 inches, etc., the elimination or subtraction of one inner block decreasing the diameter of the conduit or structure by 3 inches. Accordingly, the width of the face of the universal inner block A between the longitudinal side edges 4 must be theoretically three times pi or 9.4248 inches, but inasmuch as there is always a variation in the shrinkage of the clay material from which the blocks are usually formed, a certain allowance must be made so that in actual practice the width of the universal block A between the side edges 4 of same will be three times pi, minus a unit which is equal to the extreme variation of the shrinkage of material used in the construction of the block.

Another important point in the design of the universal block A is the angle of the side edges 4 of said block, it being necessary to have said side edges disposed at such an angle with relation to the inner surface 3 of the block that irrespective of the size of the conduit in which the block is used, it will not arch at its outer edge, and thus create an unstable arch structure. The engineering requirements with respect to the edges 4 in their relation to the edges of an adjacent block is that under all conditions the opposed edges must either be parallel or so disposed with relation to each other that they will arch at their inner element.

Now, the only design which will satisfy this requirement is that in which the edges 4 of adjacent blocks, when these blocks are assembled on the largest size conduit, shall be parallel, or approximately parallel. Then when blocks having this characteristic are assembled on any smaller form, these longitudinal side edges of two adjacent inner blocks will be substantially wedge-shaped,

with the inner elements of the edge 4 forming the apex of the wedge. This can be accomplished conveniently by providing the universal block A with longitudinal side edges 5 that are parallel, or approximately parallel, to the radius of the largest conduit of the series, as shown in Figure 5.

Another important characteristic of the universal block A is the radius of its inner face 3. Preferably, the radius of said face is as near as possible to the mean between the two extreme sizes for which the block is to serve. There is a certain deformation during the process of burning or firing blocks of this general shape. Some blocks will become flatter than they originally were and some will warp and have a greater curvature than they had when they came out of the dies. As a result of this phenomenon, by assorting the blocks and using those which have taken on the greatest curvature for building the smaller sizes of conduits, using those which have not become distorted in burning to build the middle sizes and using those that have become flattened to build the larger sizes, a very much better finished structure will result than is possible with the present method, where it is necessary to use each block in a particular sized conduit, even where that block is either more dish-shaped or flattened more than is desired.

When the outer portion of the wall of the structure is composed of segmental outer blocks or tile, as herein illustrated, there are two things which are important to the flexibility of construction and to the strength of the structure. There may be as many sizes of these outer blocks as the local conditions make necessary. In Figure 1 of the drawings I have shown four different sizes of outer blocks that are adapted to be used in the construction of fifteen sewers or conduits having different diameters. One important characteristic of said outer blocks is that they must be of such dimensions that when they are assembled the spaces between the longitudinal side edges of same will be wider than the spaces between the longitudinal side edges 4 of the inner blocks A, thereby permitting interchangeability and insuring the inner blocks A arching before the outer blocks arch, in case the form is removed before the mortar or concrete between the blocks has set, and consequently, eliminating the possibility of some of the inner blocks at the top side of the structure dropping out of position, as might occur if the outer blocks arched before the inner blocks. To state it in another way, it is essential that the outer blocks B, B', B² and B³ be of such width with relation to the width of the inner blocks A that the inner blocks A will arch or come together immediately upon the removal of the form on which the inner

blocks are laid up, and thus sustain the weight of the outer blocks at the top side of the structure, it being the usual custom to remove the form before the mortar or concrete has set.

When the outer blocks are made in the form of hollow tile provided with longitudinally-extending webs 5, it is preferable to thicken or increase the cross-sectional area of said webs adjacent the inner and outer ends of same, as indicated by the reference character 5^a in Figures 3, 4 and 5, as this greatly adds to the strength of the sewer or conduit by resisting the shear at the points where the webs 5 are joined to the inner and outer side portions of the outer blocks.

In addition to the desirable features previously pointed out, the series of sewers or conduits herein described makes it possible to meet varying conditions found in actual practice by simply arranging the units in different ways. For instance, a 57 inch sewer would ordinarily be built from inner blocks A and outer blocks B². If, however, the sewer is to be built in a location where it is subjected to greater loads than a 57 inch sewer is usually subjected to, the strength of the sewer can easily be increased by using outer blocks B³ in place of the blocks B², it being noted that the sets or groups of outer blocks B, B', B² and B³ are of gradually increasing thickness. On the other hand, if as in drainage work, the load to which the sewer will be subjected will be exceptionally light, the sewer can be constructed from inner blocks A and outer blocks B', thus effecting a considerable saving in the cost of construction.

Having thus described my invention, what I claim as new and desire to secure by Letters Patent is:

1. A method of constructing double wall sewers or conduits whose diameters vary in a certain ratio, characterized by forming the inner portions of the walls of the sewers from universal blocks of standard dimensions and forming the outer portions of said walls from outer blocks that vary in thickness according to the diameter of the sewer being constructed, and increasing the number of inner blocks and the number of outer blocks by one when a sewer of the next larger size is being constructed.

2. A system of constructing a series of double wall sewers or conduits whose diameters vary in a certain ratio, characterized by forming the inner portion of the wall of each conduit of the series from universal segmental blocks of standard dimensions and forming the outer portions of the walls of said conduits from a set of outer segmental blocks of varying thickness, adding one additional inner block and one additional outer block for each conduit of the next larger size, and selecting and using

from the set of outer blocks those blocks of as to be capable of use in the construction of the set whose thickness is best suited to carry conduits of a different size and whose outer 10 the external load imposed on the conduit. portion is constructed of segmental outer

3. A conduit or sewer forming one of a number of conduits that vary in diameter by three inches, said conduit having a double wall whose inner portion is constructed off segmental inner blocks proportioned so

WILLIAM C. EERGUSON.
